FLEXIBLE KEYCASE

Larry Simon, Outremont, Montreal, Quebec, Canada, assignor to Morey L. Simon, Outremont, Montreal, Quebec, Canada

Application May 20, 1946, Serial No. 671,053

2 Claims. (Cl. 150—40)

1

This invention relates to new and useful improvements in key cases.

An object of the invention is to provide a simple, efficient, compact, durable, economical device which can be readily carried in the pocket or in a handbag without detrimental contact of the keys with the pockets or the bag.

Another object is to provide a key case in which the keys are always held in a definite position when not in use so that they may be quickly and easily located when needed, and they will not move around and rattle and get mixed up with each other as is the situation with some forms of cases now on the market.

A further object is to provide simple means for locking and unlocking the various keys, which lock device can also be used as a support for identification means such as initials, monograms, coats of arms, club insignia, etc.

A still further object is to provide a simple compact case which is light in weight and of very small bulk so as not to be noticeable when carried in the pocket or handbag.

Further and more specific objects, features and advantages will more clearly appear from the detailed specification hereinafter set forth especially when taken in connection with the accompanying drawings which form part of the specification and which illustrate a present preferred form which the invention may assume.

In brief, and in most general terms, the invention comprises a flexible case of U-shaped cross section, keys pivotally supported between the ends of the walls of said case with their stems projecting toward the center thereof, means encircling the case and adapted when in one position to inhibit the movement of said stems from their normal position between the walls of the case, said means slideable along the case in either direction from a normal locking or inhibiting position to permit pivotal movement of one of said keys while still inhibiting the movement of the other key.

In other particulars, the middle bottom wall of the case is weakened in any suitable manner, such as by cutting it away to some degree whereby it can be flexed or bent around this weakened point whereby one-half of the case at a time may be bent when the slide sleeve or locking means is moved in one direction from the normal locking position and whereby the other half of the case may be bent around the weak point when the slide sleeve is moved in the other direction.

More particularly, the case is made of a blank of leather which is folded into a U-shape with

5 two parallel walls between which the keys are pivotally disposed with their stems extending toward each other toward the middle of the case. A lock sleeve encircles the case and slides along within limits defined by a recess cut in the top edges of the side walls which recess produces shoulders which act as stops for the movement of the sleeve. When the sleeve is in a mid position, it encircles and lies around the ends of the stems of the keys and keeps them from pivotal movement. When the sleeve is moved to one end of the recess, it moves away from its superposed position over the end of one key and thus permits that key to be pivoted into accessible position while at the same time the other key over which the sleeve still lies is held in restrained position. The half of the case containing the key which is thus released may be flexed downwardly by reason of the fact that the middle 10 of the bottom wall of the case is weakened to permit the halves to be respectively flexed down. The movement of the lock sleeve in the other direction from normal mid-position will result in similar actions taking place with respect to the 15 keys but reverse to that above described. The weakening of the case along its bottom at the middle thereof may be effected by cutting part away thus producing a nick-like notch when the blank is folded to receive the keys. The keys 20 are supported on well-known two-piece screws which may be easily removed to permit removal or insertion of keys very quickly.

25 The case is designed for carrying keys comfortably in the pocket or in a lady's bag. The covering or material thereof may be of leather or other flexible material that prevents the keys from having contact with the lining of the pocket or bag. The keys are rigidly held and they are, therefore, always in the same position and can be easily located. No rattling or jingling can take place, nor can the keys become entangled with other objects in the pocket or bag. An interlocking screw goes through each end of the case when folded through perforations made for 30 that purpose. A metal oval-shaped seamless sleeve fits over the case at its narrow portion when it is folded. This lock ring is also used for engraving or identification purposes. It is feasible to solder, weld, or rivet on to this lock sleeve, metal crests or castings received in the form of a gift or presentation from a club, business firm, or institution. The key case is very 35 light in weight and size and will not cause the pocket or bag to bulge.

40 The keys can easily be interchanged when nec-

2

essary. Any desired key can be easily reached by moving the locking sleeve to the side farthest from the key desired and releasing such key which is then ready for use. After use, the key slips back easily into place and is firmly held in position along with the other keys in the ring when the lock sleeve is moved back to locking position. In the preferred form, the case is weakened along the bottom along the foldline preferably, although not necessarily, by cutting a diamond-shaped perforation therein in the center of the length thereof which permits the ready flexing of the case around this point, to allow easy opening of the case at either end when desired and in the specific manner to be herein-after set forth.

The articles used for this purpose before this invention have consisted of metal key rings or rectangular leather devices to which keys are attached by means of hooks. These are inconvenient, the keys constantly moving out of position or becoming entangled with other objects, rattling or jingling noises are common, and the pocket or bag is torn by contact with the keys.

The inconveniences of the devices previously used for this purpose are, therefore, overcome in the manner described herein. The retention of the keys in a rigid or fixed position when not in use entirely covered by the material of the case and held in position by the lock sleeve affords protection from contact with the lining of a pocket or bag, prevents rattling and jingling, prevents entanglement with other objects, affords easy accessibility, is convenient in carrying, creates no bulge, and permits ready identification by the engraving on the lock sleeve.

The present preferred form which the invention may assume is illustrated in the drawings, of which:

Fig. 1 is a view of the flat blank from which the case is formed.

Fig. 2 is a side elevation of the case assembled, and with the parts in closed position.

Fig. 3 is a similar view showing the parts in position to permit access to some of the keys.

Fig. 4 is a vertical cross section taken on the line 4—4 of Fig. 3.

Fig. 5 is a perspective view of the sliding lock sleeve.

Fig. 6 is a detail of the screw which holds the blank in operative position and acts as a pivot for the keys.

The preferred form of the invention shown in the drawings comprises a blank 10 having a line of fold 11 around which the two halves of the blank are bent to form a U-shaped case with parallel side walls 12 and 13 connected at the bottom. The top of each side wall is provided with an elongated recess cut out therefrom, which forms projecting stop shoulders 15 at each end thereof, which shoulders are preferably inclined, as shown, to form limiting stops for a sliding oval sleeve 16 preferably of metal which encircles the case and can be slid back and forth from a central position shown in Fig. 2, to either end of the recesses 14.

The ends of the side walls 12 and 13 are perforated as at 17 and when aligned as in Fig. 2, receive connecting and pivot screws 18 made of two pieces in a well-known manner. Keys 19 are disposed between the side walls and are hung by their usual end perforations on the pivot screws, as shown, with their working ends disposed toward each other and toward the central

part of the case, which it is to be noted, is open all along the top portion thereof.

The bottom of the case is cut away as at 20, and shown in the form of a diamond so that when the blank is folded as in Fig. 2, the cut-away or weakened portion shows an indentation or nick in the bottom wall which, therefore, forms a weakened portion along the bottom wall of the case around which one or the other half 10 of the case may be bent, as will be described.

The length of the recess 14 and the length of the sliding lock sleeve 16 is such that when the sleeve 16 is in mid-locking position, it will cover and stiffen the weakened portion and lie over the free ends of both sets of keys. However, when the lock sleeve is moved to either end of the recess 14, as shown in Fig. 3, it will still lie over and lock one set of keys but will be moved away from locking position over the other set of keys and thus permit that set to be pivotally moved around their supporting pivot screw for use by the owner of the case. In this off-center position it will be seen that one side edge of the lock sleeve is abutting the stop shoulder 15 and the other side edge lies in alignment with the cut-away portion 20 so that, in this particular position of the lock sleeve, the right half of the case may be bent down as shown in Fig. 3, to permit ready access to and movement of the keys in that end of the case around their pivot points for ready use. When the lock sleeve is moved to the other end of the recess 14, the other half of the case can thus be bent down and the keys therein made accessible.

While the invention has been described in detail with respect to a present preferred form which it may assume, it is not to be limited to such details and form since many changes and modifications may be made in the invention without departing from the spirit and scope of the invention in its broadest aspects. Hence it is desired to cover any and all forms and modifications of the invention which may come within the language and scope of any one or more of the appended claims.

Having thus described my invention, what I claim as new and desire to secure by Letters Patent is:

1. A key case comprising a sheet of flexible material folded into a U-shape with spaced parallel walls, the material in the middle of the case along the bottom of the U being cut away to weaken it to permit downward flexing of either half of the case with respect to the other half, and a slidable sleeve encircling said walls and normally disposed in position to surround said weakened portion to inhibit said flexing when the sleeve is in this normal position, the upper edges of said walls being provided with cut-away elongated recesses having end shoulders acting as stops to the sleeve when it is moved in either direction from normal.

2. A key case comprising a sheet of flexible material folded into a U-shape with spaced parallel walls, the sheet in the middle at the line of fold 65 being cut away to form a weakening opening of predetermined shape, interlocking screws connecting said walls at their ends, keys pivotally supported on said screws with their stems extending toward each other, a slidable sleeve encircling 70 said walls and normally disposed to surround the weakened portion and the ends of the key stems, the upper edges of the walls being cut away in the form of elongated recesses having end shoulders acting as stops for the movement of the 75 sleeve in either direction from normal, the sleeve,

when moved to either direction from normal to the ends of said recesses, moving away from said weakened portion and from the ends of one set of keys, whereby said released keys may be pivoted out of the case and one-half of the case may be flexed downwardly with respect to the other half to facilitate access to the keys in the downwardly flexed end of the case for use.
